ABSTRACT

A coaxial cable for connecting a coaxial transmission line cable to an antenna which provides a rugged construction and provides a seal from moisture.

6 Claims, 2 Drawing SheetsFIG. 1

FIG. 2

COAXIAL CABLE CONNECTOR

This application claims the benefit of U.S. Provisional Application No. 60/102,466, filed Sep. 30, 1998.

TECHNICAL FIELD

This invention relates to a new rugged cable connector means for connecting transmission line cables to antennas and, in particular, to a unitary connector means which can be inexpensively manufactured, and yet reduce radio frequency losses through the connections.

BACKGROUND OF THE INVENTION

In the industry of radio frequency equipment, antennas are connected to transmission line cables by connectors known as SO-239 and PL-259 screw machine connectors. These screw machine connectors are expensive to produce and are difficult to assemble. Additionally, the interconnecting male-female components are subject to radio frequency losses due to corrosion in harsh environments. One early type of transmission line connection described in the Blonder U.S. Pat. No. 3,001,169 patent was comprised of many small components which had to be individually assembled and which increased the points of contact at which corrosion or radio frequency disturbances could occur. Another attempt to prevent corrosion includes the Emery U.S. Pat. No. 5,580,277, which is an earlier invention by the present inventor, which describes embedding a contact plate in a plastic body to seal the cable connections to the contact plate and a machine screw which also isolates the contact plate from the atmosphere when attached to an antenna.

SUMMARY OF THE INVENTION

The present invention generally comprises a coaxial cable connector comprising a plurality of components. An internally threaded shell body receives a plastic stepped washer inserted through one end of the shell body. The plastic stepped washer matingly engages a distal end of the threaded shell body. An extended externally threaded member having a coaxial opening is positioned in the threaded shell body. A first end of the extended threaded member passes through an opening in the plastic stepped washer and matingly engages the stepped washer. The extended threaded member does not come into contact with the threaded shell body. An insulating flat washer which conforms to the interior diameter of the threaded opening of the shell body is positioned adjacent a second end of the extended threaded member. The flat washer acts as an insulator and as a mechanical seal. The flat washer defines an axial opening extending therethrough.

A tubular threaded body having at least one, and preferably a plurality of, soldering windows is coaxially positioned in the shell body. It is to be understood that the soldering of any coaxial cable wire extending through the tubular threaded body is accomplished prior to the coaxial insertion of the tubular threaded body into the opening defined in the threaded shell body. The coaxial cable extends through the coaxial openings of the tubular threaded body, the flat washer, the threaded shell body, the stepped washer and the extended threaded member.

A tubular threaded strain relief member is coaxially positioned on the coaxial cable prior to the coaxial cable being inserted through the coaxial cable connector. The tubular threaded strain relief member can be threaded to the

tubular threaded body to provide both compression and connection of the outer wires of the coaxial cable to the tubular threaded body.

One object of the present invention is to produce a coaxial cable connector which is not susceptible to corrosion damage due to incomplete or leaky seals between the components of the connector.

Another object of this invention is to reduce the number of component parts by producing a single unitary connector, thereby reducing manufacturing costs and reducing the assembly time.

Additionally, another object of this invention is to reduce radio frequency losses that typically occur between components of a cable connector by producing a unitary connector.

Other objects and advantages of the present invention will become apparent to those skilled in the art upon a review of the following detailed description of the preferred embodiments and the accompanying drawings.

BRIEF DESCRIPTION OF THE DRAWINGS

FIG. 1 is a cross-sectional view of a coaxial cable connector.

FIG. 2 is an exploded view of the components comprising a coaxial cable connector.

DETAILED DESCRIPTION OF THE PREFERRED EMBODIMENT

A coaxial connector 10 comprises a hexagonally headed shell body 12 which has an internal threaded passageway 14. The threaded shell body 12 defines an inner shoulder or flange 16. The threaded shell body 12 has an axial extending opening 18 adjacent the shoulder 16 which extends through a hexagon head portion 19. The opening 18 is in communication with the internal threaded passageway 14. The outer shell body protects the coaxial connector from a harsh external environment and also acts as an electrical ground.

An insulating step washer 20 having a neck 22 and a shoulder 24 is positioned in the shell body 12. The step washer 20 defines a coaxial opening 26. The step washer 20 is matingly positioned within the threaded passageway 14 of the shell body 12 such that the shoulder 24 of the step washer 20 matingly engages the shoulder 16 of the shell body 12. The neck 22 of the washer 20 extends through the opening 18 of the threaded shell body 12. The neck 22 of the step washer 20 can extend beyond a planar surface of the hexagonal head portion 19.

An extended threaded member 30 has an exterior threaded shank 32 and a flange 34 that extends from one end of the threaded shank 32. The flange 34 has an external diameter which is less than an internal diameter defined by the threaded passageway 14 of the shell body 12. The extended threaded member 30 defines a first coaxial opening 36 which extends from the shoulder 34 part way into the interior of the extended threaded member 30. The first coaxial opening 36 has a first diameter. The first coaxial opening 36 is in communication with a second coaxial opening 38 which starts at the end of the extended threaded member 30 and extends into the interior of the extended threaded member 30. The second coaxial opening 38 has a second diameter that is smaller than the diameter of the first coaxial opening 36.

The shank 32 of the extended threaded member 30 is coaxially positioned within the opening 26 of the step washer 20 such that the threaded shank 32 generally extends in a direction away from the hexagon head portion 19 of the

threaded shell body 12. The step washer 20 provides insulation between the extended threaded member 30 and the outer shell body 12. A flat insulating washer 40 having a coaxial opening 42 extending therethrough is coaxially positioned within the threaded shell body 12. The opening 42 of the flat washer 40 can have the same diameter as the first coaxial opening 36 of the extended threaded member 30.

An outer conductor body 50 has a tubular section 52 which terminates at a threaded fitting 54. The threaded fitting 54 has a diameter that is in larger than the diameter of the tubular section 52. A plurality of threads 55 are positioned on the outer perimeter of the threaded fitting 54. A cylindrical body 56 extends from the threaded fitting 54 in a direction away from the tubular section 52. The cylindrical body 56 has at least one, and preferably a plurality, of windows or openings 57. The openings 57 are positioned in a radially spaced relationship around the cylindrical body 56 and extend through the cylindrical body 56. A positioning flange 58 is positioned on the end of the cylindrical body 56 that is spaced apart from threaded fitting 54. A channel 64 extends axially through the outer conductor body 50. The channel 64 has a threaded region 53 in the tubular section 52 and terminates in an opening 59 in the positioning flange 58. The flat washer 40 provides insulation between the extended threaded member 30 and an outer conductor body 50.

Before assembly, a coaxial wire 80 is at least partially stripped of insulation and inserted through the opening 64 in the outer conductor body 50. The wire 80 has an external insulated portion 82, external wires 84 positioned under the external insulation, an inner insulated portion 86 positioned under the external wires 84, and internal wires 88 positioned under the internal insulation. The internal wires 88 extend through the opening 62 in the insulating material 60 and through the first coaxial opening 36 of the extended threaded member 30. The inner insulated portion 84 of the wire 80 generally terminates in the second coaxial opening 38 of the extended threaded member 30. The external wires 84 can be soldered to the outer conductor body 50 through the openings or windows 57 of the outer conductor body 50.

The outer conductor body 50 is coaxially positioned in the shell body 12 such that the positioning flange 58 of the conductor body 50 comes into mating engagement with the flat washer 40 as the threads 55 on the threaded fitting 54 engage the threaded passageway 14 of the shell body 12.

The coaxial cable connector 10 can further include a strain relief member 70 which has a tubular member 72, and a bolt head 76 positioned on one end of the tubular member 72. A coaxial opening 78 extends through the tubular member 72 and the bolt head 76. External threads 74 are positioned on the tubular member 72 adjacent the bolt head 76. The strain relief member 70 is positioned on the wire 80 prior to the soldering of the exterior wires 84 to the outer conductor body 50. The external threads 74 matingly engage the threaded region 53 of the tubular section 52 of the outer conductor body 50. The tubular member 72 contacts the external wires 84 and compresses the wires 84 against the cylindrical body 56 of the outer conductor body 50 to aid in making a good electrical connection.

The tubular threaded strain relief member 70 provides a compression fit of the external wires 84 against the outer conductor body 50. In addition, the tubular threaded strain

relief member 70 provides strain relief between the outer conductor body 50 and the coaxial transmission wire 80.

As the various portions of the coaxial cable connector are threaded together, the individual components are compressed to ensure strength as well as to provide a seal from moisture.

The above detailed description of the present invention is given for explanatory purposes. It will be apparent to those skilled in the art that numerous changes and modifications can be made without departing from the scope of the invention. Accordingly, the whole of the foregoing description is to be construed in an illustrative and not a limitative sense, the scope of the invention being defined solely by the appended claims.

I claim:

1. A coaxial cable connector comprising:
an internally threaded shell body having a coaxial opening extending therethrough;
an insulating stepped washer having a neck and a shoulder and a coaxial opening extending therethrough, the stepped washer being coaxially positioned in the threaded shell body whereby the neck extends through the coaxial opening of the shell body;
2. The connector of claim 1, wherein the threaded shell body acts as an electrical ground.
3. The connector of claim 1, wherein the flat washer acts as a compression member of the coaxial cable connector.
4. The connector of claim 1, wherein the flat washer acts as a mechanical moisture seal.
5. The connector of claim 1, wherein a tubular threaded strain relief member is threadingly engaged within the internally threaded tubular section of the outer conductor body.
6. The connector of claim 1, wherein the threaded shell body acts as a shield from an external environment.
